UNITED STATES PATENT OFFICE

ROY V. YEAGER, OF DES MOINES, IOWA

STRUCTURAL FLOOR

Application filed February 7, 1928. Serial No. 252,524.

My invention relates to that class of structural floors in which structural metal joists are employed, and the concrete floor is supported upon said joists, with all or part of 5 the joists extended below the floor and fireproofed.

The object of my invention is to provide a structural floor of this character to which fireproofing material, such as gypsum, may be readily and easily moulded about the lower 10 portions of the joists, before the joists are placed in position, and this fireproofing material will furnish a temporary support for the plaster boards between the joists.

15 In this connection, a further object is to provide a structural joist which may be adequately fireproofed with a minimum thickness of fireproofing material. These plaster boards resting upon the fireproofing material 20 will form an adequate temporary support for the concrete floor in plastic condition, and when the floor has set and hardened, it will become bonded with the plaster board.

25 A further object of my invention is to provide a structural joist in which the top chord is made of two relatively small members spaced apart, and the lower chord made of a single member, and whereby when the upper chord has become embedded in the set and 30 hardened concrete, it will be prevented from buckling due to compression strains by the action of the concrete in which the spaced apart upper chords are embedded. In this connection it should be explained that the ordinary structural joints now in use are made 35 with the cross sectional area of the upper chord much greater than the cross sectional area of the lower chord, whereas with my improved floor construction these structural joists are preferably made with the cross sectional area of the upper chords the same as, or less than, the cross sectional area of the lower chord, thus effecting a substantial 40 saving in structural metal for the joists.

45 My invention consists in the construction, arrangement and combination of the various parts of the device, whereby the objects contemplated are attained, as hereinafter more 50 fully set forth, pointed out in my claim, and

illustrated in the accompanying drawings, in which:

Figure 1 shows a side elevation of a portion of a floor structure with fireproofing material applied to the lower portion of the 55 joists, part of which is broken away to show the lower chord member and with plaster board supported upon the fireproofing material, and shown in section, and with a concrete floor moulded upon the plaster 60 board and about the upper chord member, and shown in section.

Figure 2 shows a transverse sectional view on the line 2—2 of Figure 1; and

Figure 3 shows a transverse sectional view 65 on the line 3—3 of Figure 1.

Referring to the accompanying drawings, it will be seen that my improved joist comprises a lower chord made of one piece of metal, preferably round in cross section. 70 This chord comprises a horizontally arranged end member 10 designed to rest on the structural beams or walls, a part 11 extending downwardly therefrom at an angle of about 45°, and a horizontally arranged 75 central portion 12. Resting on top of the endmembers 10 are reinforcing blocks 13, and resting against the sides of these reinforcing blocks are the upper chord members 14 and 15. Bracing members 16 are provided to 80 connect the upper and lower chord members at intervals, and they are preferably welded to the top of the lower chord member and extended between and welded to the upper chord members. 85

The cross sectional area of the upper chord members 14 is the same as, or less than, the cross sectional area of the lower chord member.

When a floor is being constructed, a suitable mould is provided and the lower chord member of each joist is placed centrally in the mould. Then there is applied in the mould gypsum fireproofing material, or the like, in plastic condition, which very soon 90 sets and hardens, and when the joist is removed from the mould, the fireproofing material is bonded and anchored to it and forms 95 an adequate fireproofing for the lower chord member. The upper end of the fireproofing 100

material forms a horizontal shoulder which is spaced apart a considerable distance from the top chord member, which fireproofing material is indicated by the numeral 17.

5 After the joists have been laid in position, layers of plaster board 18 are placed in position between the joists and resting upon the top of the fireproofing material 17. Then the concrete floor 19 in plastic condition is placed 10 on the plaster board and surrounds and extends above the top of the upper chord members, and after the floor has set and hardened, the plaster board becomes bonded with the concrete floor.

15 In practical use, it is obvious with my improved floor structure there is effected an economy in the amount of structural metal necessary for the joists, because the lower chord has applied to it in use only tension 20 strains, and the upper chord member has applied to it only compression strains, and hence the upper chord members are embedded in rigid concrete that cannot buckle, and hence can be made with much less metal than could 25 properly be used heretofore in floor structures in which the concrete floor was placed above the upper chords.

It will be noted also that with my improved structural floor there is an economy in the 30 amount of fireproofing necessary for the lower chord, because since the lower chord is made of one piece of metal only, it is of less diameter from side to side than if it were made of two members side by side, and hence the 35 amount of fireproofing material necessary to adequately fireproof it is greatly reduced.

I claim as my invention:

In a structural floor, the combination of a number of structural joists, each comprising 40 a top chord made of two parallel chord members spaced apart laterally, a single lower chord member connected at its ends to the upper chord member with its central portion spaced below the upper chord member, braces 45 secured to the lower chord member and projected between and secured to the upper chord members, the transverse dimensions of the two upper chord members being much greater than the transverse diameter of the 50 single lower chord member, a body of fireproof material for each beam moulded about and bonded to and completely surrounding the lower portion of each beam, and having at its upper portion supporting shoulders 55 extended laterally, plaster boards supported upon said shoulders and extended from one beam to the other, and a concrete floor supported upon the plaster boards and completely surrounding and bonding the upper portions 60 of the beams.

Des Moines, Iowa, January 20, 1928.

ROY V. YEAGER.
